UNITED STATES PATENT OFFICE.

WILLIAM S. ATWOOD AND FRANK DITCHFIELD, OF MONTREAL, QUEBEC, CANADA.

RAILWAY-CAR.

1,085,099.

Specification of Letters Patent.

Patented Jan. 27, 1914.

Original application filed July 11, 1910, Serial No. 571,327. Divided and this application filed March 13, 1911. Serial No. 613,968.

To all whom it may concern:

Be it known that we, WILLIAM S. ATWOOD and FRANK DITCHFIELD, both of the city of Montreal, in the Province of Quebec and 5 Dominion of Canada, have invented certain new and useful Improvements in Railway-Cars, and do hereby declare that the following is a full, clear, and exact description of the invention, such as will enable others 10 skilled in the art to which it appertains to make and use the same.

This invention relates to railway cars and is particularly adapted to be used in the construction of metallic freight or box cars, 15 although several features of construction may be adapted for use in the construction of passenger cars.

The main object of the invention is to provide a metal car of neat appearance, com- 20 paratively inexpensive construction, but possessing great strength and durability.

A further object is to provide a car that can be properly ventilated at all times without subjecting the interior to drafts, and 25 without liability of leakage through the ventilating apertures.

The invention consists essentially of a car having an underframe of the usual type but having its sides, ends and roof consisting of 30 sheet metal plates, said plates being provided at intervals with vertical integral ribs or corrugations and being so constructed and arranged that continuous ventilating flues or conduits are provided which extend from the 35 bottom of the sides upwardly to the roof, said flues being provided on the interior of the car with suitable apertures for admitting air to the interior thereof. By this means, the ribs form vertical strengthening mem- 40 bers or stakes for the sides of the car, said ribs at the same time comprising ventilating flues which prevent the interior of the car from sweating or becoming damp, as is fully set forth in my co-pending application, Ser. 45 No. 571,327, filed July 11th, 1910, of which this application is a division.

In the accompanying drawings which illustrate our invention and in which similar numerals of reference refer to similar parts 50 thereof Figure 1 is a partial side elevation of a car constructed according to our in-

vention. Fig. 2 shows on the left half, a partial plan view, and on the right, a partial horizontal section, on the line 10—11 of Fig. 1. Fig. 3 is an end elevation of the car. 55 Fig. 4 shows, on the left half, a cross section on the line 12—13, and on the right, a cross section on the line 14—15 of Fig. 1. Fig. 5 is a partial cross section showing the air flues. Fig. 6 is a detailed cross section of 60 one of the flues. Fig. 7 is an enlarged partial vertical cross section on the line 14—15 of Fig. 1, showing the arrangement of the doors. Fig. 8 is an enlarged partial horizontal cross section on the line 10—11 of 65 Fig. 1, showing the arrangement of the doors. Fig. 9 is a slightly modified form of the flue shown in Fig. 6, adapted for passenger car construction.

Referring more particularly to the parts, 70 16 designates the center sills, 17 the side sills, and 18 the body bolsters, 19 the cross bearers or transoms, 20 the end sills, and 21 the longitudinal floor joists comprising the under-frame of the car and arranged in the 75 usual manner and according to the best approved construction. The floor boards 22 are laid transversely across the joists 21, forming a permanent floor for the car, although it will be obvious that the construction hereinafter described may be used with 80 hopper bottom cars.

The sides, ends and roof of the car are constructed of sheet metal plates, the interior surface being plain and smooth, while 85 the outside of the car has a series of vertical ribs or stakes at intervals along the length thereof, said ribs extending over the roof and being continuous with the sides. These ribs are formed by crimping or corrugating 90 the metal plates of which the upper frame is constructed, the ribs being U-shaped, as shown in Figs. 6 and 9, and the edges of the plates being slightly offset so that the overlapping ends of the adjoining plate may be 95 fitted thereon to form a smooth or plain joint in the interior of the car. The vertical side plates 23 are riveted at the bottom to the angle sections forming the side sills of the car and are riveted at the top to the roof 100 plates. The edges of the plates 23 are offset as indicated at 24 so that the adjoining

plate which over-laps the rib will fit closely without allowing the ridge to project from the surface. The U-shaped ribs 25, formed by corrugating the plates, are of such area in cross section as to permit a large volume of air to circulate therethrough and the plates are overlapped in such a manner as to allow the ribs to run continuously from the bottom of the car to the top and over the roof, the ribs thus constituting ventilating flues. The plates 23 are overlapped, as indicated in Fig. 6, across the ribs and are connected by means of suitable rivets 26 through the flanges on each side of the ribs 27 designates the end plates of the car, said plates being connected by the vertical connecting strip 27^a. The end plates 27 and side plates 23 are bound together by the corner angle sections 28. At the ends of the car, transverse filler plates 29 are inserted below the roof plates to take up the pitch of the roof, as indicated in Figs. 3 and 4.

The transverse roof plates 30 may extend across the car, or may be united at the center 25 of the car, and are bent over and downwardly at the sides to connect with the side plates. These roof plates are provided with ribs 31 of the same contour as the ribs 25 on the side plates, but slightly larger in 30 order that the ribs 31 will overlap the ribs 25 forming a tight joint. These ribs 31 form the carlines of the roof and are turned downwardly as indicated at 32. The interior of the roof peak is provided with a longitudinal central air channel 33, which serves not only to brace and unite the roof plates when they are formed in two sections, but is further adapted to permit the air from the flues to be distributed through the 40 cars. The roof plates are riveted to the side plates, and corner braces 34 serve further to strengthen the car frame.

Within the ribs or carlines 31, we provide apertures 35 which open into the central air 45 channel 33 and may, if desired, open directly into the interior of the car, as indicated in Fig. 5. Apertures 36 in the air channel 33 permit the air to be distributed from end to end of the car. It will thus be 50 seen that the flues which are open at the bottom will permit air to be drawn upwardly at the sides of the car and distributed evenly at the roof, the side stakes and carlines forming continuous flues for this 55 system of ventilation.

A foot-walk 37 supported on the brackets 37^a, extend along the car roof. A filler 38 inserted at the juncture of the floor and sides prevents grain and like material from 60 lodging in the corners. To strengthen and stiffen the car sides, we may, in some cases, use the longitudinal U-shaped stiffeners 39 extending from end to end of the car and riveted to the interior at suitable intervals. 65 The ends of the car are strengthened by the

transverse stiffeners 40, the ends 41 of which taper off as indicated in Fig. 2.

The doorways 42 at the sides of the car are closed by sliding doors somewhat in the usual manner. At the doorways, the floor 70 extends outwardly a suitable distance, being supported upon the extension angles 43. The door 44 consists of a metal plate stiffened at the edges by peripheral flanges 45 and at the top by an angle bar 45^a. At one 75 side the vertical Z-bar 46 forms the locking jamb, while the channel section 47 forms the door jamb at the opposite side. The sealing plate 48 extends along the edge of the door and overlaps the channel 47. The 80 lintel or top sill 49 is formed of a Z-bar having one flange riveted to the sides of the car, and having its outer flange overhanging the top of the door. The top of the Z-bar 49 forms the track for the running wheels 85 51, which are secured to the door in any approved manner. The lintel or top sill is supported at each end by suitable brackets 52. For passenger car construction, the ribs are slightly modified in form, the ends 53 90 being flattened in order to secure same to the outside plate 54. The ribs 25 will, however, be similar in other respects, constituting ventilating flues and supports as above described. These flues may be provided with 95 dampers 55 at the bottom, or may be provided with sliding dampers in the interior of the car.

It will be seen that this construction of car besides being neat in appearance, will be 100 very strong and durable, and will be particularly adapted for carrying such freight as requires ventilation without exposure to rain or moisture. The car is well adapted for carrying live stock and, for this purpose, apertures for the admission of air may be made in the flues at the interior of the sides of the car. For carrying grain, fruit, meat and the like, this construction of car will eliminate sweating or the accumulation 105 of moisture, which is one of the greatest difficulties heretofore experienced in connection with the use of metal freight cars.

It will also be obvious that for passenger cars, this system of ventilation will afford 110 great advantages over any system that can be used in cars of other types.

While we have shown the preferred form of construction, it will be apparent that many modifications may be made without 115 departing from the spirit of our invention.

Having thus described our invention, what we claim is:—

1. In a metal car, side, end or roof plates arranged in overlapping relation, the outer 120 overlapping portion being offset to receive the inner overlapping portion, whereby smooth inner surface is formed, and ribs upset at the center of said offset overlapping portion.

2. In a metal car, side, end or roof plates arranged in overlapping relation, the outer overlapping portion being offset to receive the inner portion, flat topped ribs upset at the center of said offset plate portions, and an outer covering extending from rib to rib and secured to the flat tops thereof.

In witness whereof we have hereunto set our hands in the presence of two witnesses.

WILLIAM S. ATWOOD.
FRANK DITCHFIELD.
